DRAFT RIGGING

Filed May 7, 1928

FIG. 1

FIG. 2

Inventor
Donald S. Barrows

By *Frank J. Peckham*
Attorney

UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

DRAFT RIGGING

Application filed May 7, 1928. Serial No. 275,729.

This invention relates to railway draft rigging and more particularly to a combined backstop and center filler casting normally adapted for use with a horizontal yoke and 5 supplemental castings for connection thereto to adapt said combined casting for use with a vertical yoke.

The principal object of my invention, generally considered, is to provide a backstop preferably functioning as a bolster center filler casting and provided with a front face normally adapted to be engaged by a horizontal yoke and rear stop lug portions adapted for connection to said front face 15 and the associated sills of the car for adapting said casting for use with a vertical yoke, said yoke normally extending between the lug portions with the associated follower engaging the front faces of said lug portions.

Another object of my invention is to provide a backstop normally adapted for use with a horizontal yoke and means for converting said backstop for use with a vertical yoke, said means being readily applied 25 or removed, as desired.

A further object of my invention is to provide stop lugs which are adapted for connection to the front face of a standard backstop and bolster center filler casting for 30 adapting or converting said casting which is normally used with a horizontal yoke for use with a vertical yoke and associated rear follower, said stop lugs providing abutments for said rear follower.

Other objects and advantages of the invention relating to the particular arrangement and construction of the various parts will become apparent as the description 35 proceeds.

Referring to the drawings illustrating my invention, the scope whereof is defined by the appended claims:

Figure 1 is a partial plan and partial horizontal sectional view on the line 1—1 of Figure 2, showing one embodiment of my convertible backstop with portions of the associated sills and other parts of the car.

Figure 2 is a vertical central longitudinal sectional view of the embodiment shown in 50 Figure 1.

Referring to the drawings in detail, like parts being designated by like reference characters, a backstop and bolster center filler casting 1 is shown with side walls 2 connected to associated center or draft sills 3 by a plurality of rivets 4. Said backstop preferably, but not necessarily, functions as a bolster center filler casting, the associated bolster plates being indicated at 5, the top bolster cover plate at 6, and the bottom 60 bolster cover plate at 7. The sill cover plate is indicated at 8.

The present embodiment of my backstop casting 1 involves a transversely extending front wall 9 adapted for engagement with the rear end of a horizontal yoke in a well-known manner, such as disclosed in Figure 5 of the patent to Wright #1,458,792, dated June 12, 1923. For improving the strength of said front wall, the side portions 10 thereof preferably extend diagonally to meet the front portions of the side walls 2 of the casting. The rearward portions of the side walls are preferably connected by a rear wall 11, which is desirably alined with the webs of 75 the rear bolster plates 5, as illustrated. Said casting is also desirably formed with a bottom wall 12 and a top wall 13, said walls preferably alining with the corresponding flanges of the center sills 3, which in the present embodiment are channel shaped in section with outstanding flanges.

Extending upwardly from the bottom wall 12 of the casting is a hollow cylindrical or thimble portion 14 which provides a king pin aperture 15 and the bottom bolster cover plate is similarly apertured, as shown in Figure 2. For rigidifying the casting and tying the front and rear walls together and to the thimble portion 14, a horizontal wall or web 16 is provided which preferably extends in the plane of the center line of draft from the front wall 9 to the rear wall 11, surrounds the thimble portion 14 and extends between and connects the side walls 2. For further rigidifying the front wall of the casting, vertical walls 17 are provided which extend from said front wall to the rear wall. The intermediate or central web 17 preferably tapers 85 upwardly and downwardly to form a rela- 100

tively narrow reinforcing web, as illustrated most clearly in Figure 2. The side or outer flanges or webs 17 preferably converge slightly toward each other and flare downwardly to connect with the bottom wall 12 and upwardly to connect with the top wall 13, as illustrated, whereby they form tie webs between the front, rear, top and bottom walls of the casting.

10 The casting is further tied together transversely by an intermediate web 18 which extends between the side walls and top and bottom walls of the casting and connects said walls together and to the thimble portion 14 of said casting, an aperture 19 being provided above the thimble portion, and that portion of the wall defining the upper part of said aperture being formed with a horizontal flange portion 20. Such casting as has been 20 just described functions admirably for use with a horizontal yoke as well as a bolster center filler casting, as will be understood.

It is sometimes desirable to use a casting identical with the backstop casting heretofore described, but instead of using a horizontal yoke and Farlow attachments, to use a vertical yoke and rear draft lugs for connecting with the associated rear follower. In the patent to Wright heretofore referred to, a backstop is there disclosed which is adapted for use with either a vertical or horizontal yoke but which for that purpose is necessarily reversed in position and involves integral lug portions which add to the weight of said casting, without performing any useful function, except when employed with a vertical yoke. In accordance with the present invention, I accomplish the same purpose intended by the patent referred to without adding unnecessary weight to the casting and without making it necessary to reverse said casting for adapting it for use with a vertical yoke.

In accordance with my invention, therefore, I employ draft lug castings or auxiliary members 21 which have side webs 22 normally connected to the associated sills 3 by a plurality of rivets 23, the front edges of said walls or webs 22 being formed with inwardly extending web portions 24 which function as stop lug portions for engagement with the movable element of an associated draft gear or rear follower 25, indicated diagrammatically in dot and dash lines, associated with the vertical yoke, indicated diagrammatically by dot and dash lines at 26.

A preferred construction of said stop lug castings 21 involves approximately horizontal web or flange portions 27 extending rearwardly from the stop web 24, one at the upper edge, which preferably tapers to the rear end of the side wall portions 22, and two intermediate the upper and lower edges of said casting. The lower edge of said casting in the present embodiment is slightly

sloping upwardly from the front to the rear of the casting and is bordered by a corresponding flange 28, which preferably tapers like the upper flange 27. The upper and adjacent flanges or webs 27 and the lower and 70 adjacent flanges 28 and 27, respectively, are connected by the side wall portions 22 of the casting at their outer edges and the intermediate flanges or webs 27 are connected by inner wall portions 29 at their inner edges, 75 said inner wall portions preferably extending from the inner edges of the stop web portions 24 to the front face or web 9 of the associated backstop casting 1, where they are flanged inwardly or toward each other, as indicated at 30, to provide connecting lug or flange portions, preferably for receiving an attaching rivet or other suitable connecting means 31. The connection between the web portions 29 and 30 is preferably rigidified by 80 means of a triangular gusset portion 32.

From the foregoing description, taken in connection with the accompanying drawings, it will be seen that I have devised a backstop casting which is normally adapted 90 for use with a horizontal yoke but which, without being oversize or without necessitating reversal, may be converted for use with a vertical yoke by the connection to its front face of a pair of stop lug or vertical 95 yoke adapter castings, which are also formed for rigid connection with the associated sills of a car.

Having thus described my invention, I claim:

1. An adapter casting comprising a vertical wall portion formed for connection to an associated sill, a vertical wall portion extending at right angles thereto and adapted to function as a rear stop lug, horizontal 105 walls extending therebetween for rigidifying the construction, a vertical wall extending from the edge of said stop lug portion farthest from the first-mentioned connecting wall portion and diverging slightly from 110 said wall portion, and means connecting adjacent portions of said vertical walls, the edge of said diverging wall farthest from said connecting wall being bent and continued transversely away from said connecting 115 wall and adapted for connection to a backstop casting.

2. An adapter member comprising a wall portion formed for connection to an associated sill, a lug provided thereon to act as 120 stop means for a movable element of a draft gear, a wall extending from said lug in spaced relation to the first-mentioned wall, and means connecting said last-named wall to the first-named wall and lug, the end of 125 said last-named wall remote from the lug being bent to form means to attach said adapter to a bolster member.

3. An adapter member comprising a web formed for connection to an associated sill, 130

a lug formed thereon and adapted to act as stop means for a draft gear follower, and a web extending from said lug in spaced relation to the first-mentioned web, and horizontal web means connecting said webs and lug, the end of the second-named web having an angular extension, spaced from the lug, adapted for connection to an associated backstop.

10 4. In combination with the draft sills of a car, a backstop disposed therebetween and connected thereto, an adapter member comprising a wall portion connected to a sill, a lug formed on said wall portion to act as stop means for a movable element of a draft gear, a wall extending from said lug in spaced relation to the first-mentioned wall, and means connecting said last-named wall to the first-named wall and lug, the last-named wall being provided with an angularly disposed portion connected to the front wall of the backstop.

In testimony whereof I affix my signature.
DONALD S. BARROWS.
